(57) **CLAIM**

The ornamental design for a container for cooling beverages of any kind contained in any kind of container, as shown and described.

DESCRIPTION

FIG. 1 is a top view of a container for cooling beverages of any kind contained in any kind of container showing our new design;

FIG. 2 is a front, left side and top perspective view thereof; FIG. 3 is a back, right side and top perspective view thereof; FIG. 4 is a right side view with the opposite side being a mirror image thereof;

FIG. 5 is a front view thereof;

FIG. 6 is a back view thereof; and,

FIG. 7 is a bottom view thereof.

The broken lines and areas within the broken lines illustrate portions of the holder that form no part of the claimed design.
